UNITED STATES PATENT OFFICE.

ALBERT E. JOHNSON, OF BEVERLY, MASSACHUSETTS, ASSIGNOR TO UNITED SHOE MACHINERY COMPANY, OF PATERSON, NEW JERSEY, A CORPORATION OF NEW JERSEY.

TURNSOLE.

1,200,114.

Specification of Letters Patent.

Patented Oct. 3, 1916.

Application filed January 5, 1912. Serial No. 669,568.

To all whom it may concern:

Be it known that I, ALBERT E. JOHNSON, a citizen of the United States, residing at Beverly, in the county of Essex and State 5 of Massachusetts, have invented certain new and useful Improvements in Turnsoles; and I do hereby declare the following to be a full, clear, and exact description of the invention, such as will enable others skilled in the 10 art to which it appertains to make and use the same.

The present invention relates to improvements in outsoles for use in the manufacture of boots and shoes, and is more particularly applicable to shouldered outsoles which are used principally in the manufacture of turned shoes.

It has been customary heretofore to make a turn sole from a sole shaped blank by providing it with a marginal channel as in the making of a welt insole and with a parallel shoulder outside of the channel. The channeling and shouldering operations are usually performed simultaneously by means 25 of two knives fitted in one machine. The shouldering knife is provided with a horizontal cutting portion which splits the edge of the sole a predetermined distance from its grain side, and with a vertical cutting 30 portion which forms the shoulder by separating the string from the body portion of the sole. The edge of the sole thus produced is thinner than the body portion of the sole, within the shoulder cut, by the 35 depth of the shoulder. This shoulder is provided to form a striking surface for the curved needle used in sewing the upper to the sole which penetrates the body portion of the sole from the base of the shoulder to 40 the channel. This narrow strip of stock between the shoulder and the channel is called by those skilled in the art the "between substance." In actual practice it is found that the depth of the shoulder has 45 considerable bearing upon the effectiveness of the sewing operation. A deep shoulder provides a substantial striking surface for the needle and forms a clearly defined line to draw the upper into, thus giving a tight 50 seam. A deep shoulder, however, in the usual type of turn sole, can only be obtained by using a body portion which is comparatively thick so that when the string is removed the marginal portion will have sufficient stock to furnish the necessary wear and

provide a substantial edge thickness. As the length of wear of a turned shoe is determined by the thickness of the marginal portion of the sole beneath the cuts, the extra thickness of the central portion of the body 60 of the sole adds materially to the cost of the sole without increasing the wearing qualities of the shoe. This method of making turn soles is wasteful of the expensive leather stock.

The object of the present invention is to produce a novel turn sole, provided with a substantial striking shoulder, which is formed without using the excessively thick 70 stock heretofore found necessary in the manufacture of turn soles.

With this object in view a feature of the present invention contemplates the manufacture of a turn sole consisting of a body portion having a marginal lip cut therefrom 75 which is permanently folded over on the between substance to form a substantial striking shoulder. By folding the lip over upon the between substance a shoulder is obtained which is twice as deep as the depth of penetration of the lip forming knife, or, stated in another way, twice as deep as the material displaced from the marginal portion of the sole. A substantial striking shoulder is thus obtained without seriously affecting 80 the wearing qualities of the marginal portion of the sole.

Broadly considered the lip may be formed in the body portion of the sole in any manner found desirable or expedient. In order, however, to preserve the thickness of the sole edge the lip preferably is cut in the same face of the sole as the flap. This manner of forming the lip forms an important feature of applicant's invention. A turn sole having a substantial striking shoulder and an unreduced sole edge is particularly valuable for use in the manufacture of light soled turned footwear, such, for instance, as slippers. The soles of such footwear are often made from comparatively thin stock. Heretofore in the manufacture of this type of turned footwear, it has been necessary to employ an excessively thick body portion for the sole so that a proper striking shoulder of sufficient depth could be produced on the margin and sufficient material preserved to provide the desired thickness for the sole edge. The turn sole of the present invention is provided with a striking shoulder 100 105 110

which is formed without substantial effect on the thickness of the sole edge, and, therefore, by the use of the present invention, much thinner stock than heretofore used 5 may be used for turn soles in slipper and similar work.

Another important feature of the invention 10 contemplates the provision, in a turn sole provided with a marginal flap and a shoulder on one face, of a sheet of reinforcing material secured to the surface of said face and up the inner surface of the flap. As is well known to those skilled in the art, there is an important economic advantage in 15 reinforcing leather parts used in the manufacture of leather shoes as by this means thin or poor stock, not ordinarily available, may advantageously be utilized. A turn sole provided with a marginal flap and a shoulder on one face, may be advantageously 20 reinforced so as to permit the use of thin or poor stock. The sheet of reinforcing fabric is applied after the sole has been molded and dried, for, as will readily occur 25 to those skilled in the art, if applied before the molding operation, the subsequent tempering of the reinforced sole would be objectionable. So far as the inventor is now aware, a turn sole reinforced to permit 30 economy in the use of stock has never been produced heretofore, owing chiefly to the necessary wasteful methods of manufacture.

In the accompanying drawings illustrating 35 the best form of the invention at present devised, Figure 1 is a plan of the channeled blank; Fig. 2 is a plan of the molded blank; Fig. 3 is a transverse section on line 3 of Fig. 1; Fig. 4 is a transverse section on line 4 of Fig. 2; Fig. 5 is an enlarged perspective showing the preferred manner in 40 which the blank is channeled; Fig. 6 shows one way in which the channeled blank may be molded; and Fig. 7 shows one way in which the reinforcing material may be applied to the molded blank.

In the illustrated embodiment of the invention a sole shaped blank 1 from which the turn sole is made is first tempered and is then passed through a channeling machine such as illustrated and described in 50 the United States Letters Patent to William C. Meyer, No. 984,773, dated February 21, 1911, to which patent reference may be had for a full disclosure of the construction 55 and operation of the machine. The channeling of the blank is performed by a channel knife 2, an edge knife 3, and the flap is set by a hammer 4. The edge knife 3 is designed to cut into the blank on a slight 60 angle, eighteen degrees having been found effective, and is arranged in the machine so that its cut is started on the flesh side of the blank just within its edge. The knives thus cut a flap 7 and a lip 6 both on the same 65 face of the blank without reducing the edge

thickness. The marginal portion of the channeled blank is then passed through a molding machine. This machine is provided with a set of coöperating molding rolls comprising a sole supporting and bending roll 5, a flap setting roll 8, an edge and lip molding roll 9. The roll 9 is provided with edge molding faces and lip folding faces indicated at 10 and 11 respectively. The outer end of the roll 9 has teeth formed 70 upon its periphery which engage the edge of the sole and aid in feeding the sole through the machine. The edge molding and lip folding faces of the roll 9 are arranged to engage the feather of the sole 75 and the lip to form a vertical striking shoulder from the material of the lip, and fold the upper portion of the lip permanently over upon the between substance 12. The roll 9 also supports the flap while it is 80 set by the roll 8.

Referring now to Fig. 4 it is seen that the striking shoulder 13 is formed by folding over upon, and into contact with the between substance the material cut from the 90 marginal portion of the sole. The depth of the striking shoulder 13 is substantially twice the depth of penetration of the lip forming knife or the material displaced from the marginal portion. By this construction the striking shoulder is formed without seriously weakening the marginal portion of the sole. As it is not necessary 95 to employ an excessively thick body portion for the sole an important economy in the 100 use of stock is effected.

In the manufacture of turn shoes the upper is drawn in against the shoulder of a channeled outsole. This shoulder must have a distinct depth for holding the upper, since 105 the shoulder defines the outline of the base of the upper. Different kinds of material require different depths of shoulder, but the average depth for men's and women's work is about 3/32 of an inch. With firm, solid 110 leather the minimum depth is about 1/16 of an inch, and with soft, fleshy leather the depth is about 1/8 of an inch. In making applicant's turn sole, the lip is made a thickness of slightly over 1/32 of an inch, and 115 when it is molded and set upon the between substance gives an average height of about 3/32 of an inch. For the purpose of convenience, a shoulder on soles for men's and women's work having an average depth of 120 3/32 of an inch and a minimum depth of about 1/16 of an inch, according to the leather used, will be termed a "regular shoulder."

As is well known to those skilled in the 125 art, the use of thin leather stock in the manufacture of insoles for boots and shoes has been made possible by reinforcement of the stock with a textile fabric. The economic advantage of reinforcing insoles is well 130

known. Heretofore, owing to the wasteful method of manufacture, it was not possible to employ thin stock for turn soles and reinforce the stock with a textile fabric. The 5 turn sole of the present invention being substantially uniform in thickness may be made from thin or poor stock not ordinarily available for use in turn soles and the sole brought to the necessary strength by a sheet 10 of reinforcing fabric.

After the blank is molded and dried a sheet of sticky reinforcing fabric may be roughly applied to the face of the blank. The blank and sheet are then passed through 15 a reinforcing machine suitably designed to preserve the molded shape of the sole. In its preferred form this machine is provided with sole supporting rolls 14 and 15, a reinforcing or fabric setting roll 16, a fabric 20 trimming knife 17, and a knife guard 18. The roll 15 is provided with suitable faces to engage the feather and the folded lip and also with a rounded face 19 coöperating with the reinforcing roll to mold or bend the 25 flap inward at an inclination to the surface of the sole. The reinforcing roll is shaped to set the fabric against the surface of the sole well down into the channel angle and up the inner face of the inwardly bent flap. 30 The knife 17 coöperates with the edge 20 of the roll 15 to shear off the portion of the fabric extending above the upper edge of the flap. A toothed disk 21 may also be provided which acts as a fabric clearer. 35 The method of making the turn sole as described above is not claimed in this application, as it is being claimed in my divisional application, Serial No. 54,584, filed October 7, 1915.

40 While the various operations on the sole have been described as machine operations, as it is preferred to use machines, nevertheless, it will be obvious to those skilled in the art that all of the steps described may be 45 performed by hand, even to the application and trimming of the reinforcing fabric.

What is claimed as new is:—

1. A turn sole consisting of a body portion having a thin wedge-shaped lip cut therefrom which has a thickness substantially less than the depth of a regular shoulder and permanently molded over and set upon 50

the between substance to build up a striking shoulder of regular depth, substantially as described.

55

2. A turn sole consisting of a body portion having a flap and a thin lip cut entirely from one face of the body portion, said flap and lip having a thickness substantially less than the depth of a regular shoulder, said 60 lip being molded over and set upon the between substance at the base of the flap to build up a striking shoulder of regular depth, substantially as described.

65

3. A turn sole consisting of a body portion having a channel formed in one face and a parallel, marginal, solid shoulder outside of the channel formed by displacing material from the marginal portion of the sole, said shoulder having a depth substantially twice the depth of the material displaced from the marginal portion, and substantially the depth of a regular striking shoulder, substantially as described.

70

4. A turn sole consisting of a body portion having a flap and a lip cut from one face of the body portion, said lip being folded over upon the between substance to form a substantial striking shoulder, and a sheet of reinforcing material secured to the lipped 80 face of the body portion and to the inner surface of the flap, substantially as described.

75

5. A turn sole consisting of a body portion having a channel, channel flap and an outer marginal, striking shoulder on one face and a sheet of reinforcing material secured to said face across the channel and to the inner surface of the flap, substantially as described.

85

6. A turn sole consisting of a body portion having a thin wedge-shaped lip having a thickness at its base substantially one-half the depth of a regular shoulder, which is formed by cutting downwardly and inwardly 95 along a portion of the margin of said body portion and which is permanently molded upon the between substance to build up a striking shoulder of regular depth, substantially as described.
